JOHN F. METTEN, OF PHILADELPHIA, PENNSYLVANIA, ASSIGNOR TO THE WM. CRAMP & SONS SHIP & ENGINE BUILDING COMPANY, A CORPORATION OF PENNSYLVANIA.

STEAM-TURBINE.

1,141,473.

Specification of Letters Patent.

Patented June 1, 1915.

Application filed July 6, 1912. Serial No. 707,978.

To all whom it may concern:

Be it known that I, JOHN F. METTEN, a citizen of the United States, residing at Philadelphia, in the county of Philadelphia and State of Pennsylvania, have invented 5 certain new and useful Improvements in Steam-Turbines, of which the following is a full, clear, and exact specification.

This invention relates to improvements in 10 blading for steam turbines, and has particular reference to means for preventing eddying which results when the stream of elastic propelling fluid strikes corners and recesses in the passages, as turbines are ordinarily 15 constructed.

In turbines as ordinarily constructed, the apparent axial clearance between the stationary and the moving blades is less than the actual distance traveled by the steam 20 from the exit of one blade passage to the entrance of the succeeding one. The width of the space through which the steam actually travels is thus considerably wider between the blades than the length of travel 25 between the blades, which causes the stream to spread to some extent and thereby cause eddying where the extreme portions of the stream strike against the flat sides of the shrouding, both on the moving and the fixed 30 blades, and also on the projections or blade-carrying shoulders of the elements, as turbines are ordinarily constructed.

According to this invention, eddying between the blades is obviated by angling the 35 shoulders of the blading grooves both on the rotor and stator on the entrance side, and also making the shrouding on the blades angled on the same side. The flaring of the shrouding on the entrance side also has the 40 effect of giving its periphery a sharp edge, which largely reduces leakage past the blade tips; the tendency being to deflect the spreading edges of the stream toward the center of the passage and thereby tend to 45 keep practically the entire stream centered through the passage, without wasted, eddy expansion or leakage.

In the accompanying drawings, Figure 1 represents in longitudinal section, a portion 50 of a turbine embodying the invention; and Fig. 2 represents a section through adjoining stationary and fixed blades taken on the line 2, 2 of Fig. 1.

1 represents a peripheral section of a rotor 55 or wheel having peripheral slots 2 in whi

moving blades 3 will be fastened, the blades being separated by caulking strips 4 and rigidly fastened in any approved manner, 5 being the base of the blade fitting into the slot 2 and undercut as at 6 so that the blade will rest firmly on the peripheral shoulder 7 of the rotor 1. The peripheral shoulders 7 on the rotor are beveled on the entrance side as at 8, the blade 3 being correspondingly cut 60 so as to fit firmly on the beveled face 8, as 65 shown in Fig. 1.

9 represents the stator having slots 10 in which the bases 11 of stationary blades 12, are fastened in a similar manner.

13 represents peripheral shoulders similar 70 to 7 and 14 inclines similar to 8, suitable fastening and spacing means being provided for the blades 12, as will be well understood.

16 represent shroud rings for the stationary blades 12, the same being fastened thereto as by heads 17 and being provided with outwardly inclined surfaces 18 on the entering side, forming sharp edges 19 below the bases of the moving blades 12. 75

20 represents a shroud ring for the moving blades 3 having the inwardly inclined entering surface 21 forming a sharp edge 22 on the entering side, which, as will be seen from Fig. 1, will be outside of the base of 80 the adjacent fixed blade 12.

From the foregoing, assuming the direction of steam flow to be from left to right in the direction of the arrow, Fig. 1, it will be seen that steam striking the inclines 14 adjacent the base of the fixed blades 12 will be deflected inwardly, while steam striking the tips of the fixed blades will be guided outwardly by the surface 18 and the edges 19, the result being that eddies will be prevented and the steam directed toward the center of the passage and the main body of the flow. In like manner, the inclines 18 at the bases of the moving blades 3 and the inclines 21, with edges 22 of the shroud ring 100 at the tips of the moving blades, will direct the steam at the edges of flow toward the center of the passage and the main body of flow. 95

While it would be within the scope of this 105 invention to bevel the leaving sides of the shroud rings and the shoulders 7, 13, it might affect the clearance and is not ordinarily necessary since the steam, in leaving the bases and tips of the blades, will cover 110

most of the clearance space before it begins to eddy and at which points are placed the inclined shoulders and shroud rings for the purpose of preventing such eddies. In Fig. 5 2, the line A represents the axial clearance between the stationary and moving blades, but the line B represents the general path of the steam, it being seen, however, that the spaces transversely of the line B into which 10 the steam can eddy considerably exceed the travel of the steam in passing from one set of blades to the next in an ordinary turbine not provided with the beveled shoulders and shroud rings coöperating as herein described.

While the invention has been described for steam turbines, it is applicable to other forms of expansion fluid turbines without substantial modification, and various 20 changes in the details of construction herein shown may also be made without departure from the invention.

Having thus described my invention, I declare that what I claim as new and desire 25 to secure by Letters Patent is:

1. A shroud ring for connecting the moving blades of a turbine having its entering side coned outwardly with a sharp edge at the points of greatest diameter at the blade 30 tips to direct the fluid flow inwardly.
2. In a turbine, the combination with a turbine element having a circumferential beveled shoulder, and projecting blades supported by said shoulder, of a shroud ring 35 carried by said blades, said shroud ring having an oppositely beveled surface coöperating with said beveled surface to concentrate the flow.
3. In a turbine, the combination with a 40 stationary element having an internally projecting beveled shoulder, and internally projecting blades supported by said shoulder, of a movable element separated from said stationary element to form a fluid passage 45 and having a circumferential beveled shoulder axially displaced from the shoulder of said stationary element, said beveled portions being inclined in the direction of flow toward the middle of said fluid passage, of 50 moving blades supported by the shoulder of said moving element, the entrance portions of said blades overlying said beveled portions.
4. In a turbine, the combination with a

stationary element having inwardly projecting blades, of a shroud ring carried thereby having one side beveled from the blade tips inwardly, and a movable element having outwardly projecting blades axially displaced from said stationary blades, and a 60 shroud ring carried by said moving blades having its side corresponding to the beveled side of said stationary ring beveled outwardly.

5. The combination with stationary blades 65 having a shroud ring beveled outwardly from the entering sides of the blades, of oppositely projecting axially displaced movable blades having a shroud ring beveled oppositely to the bevel of said stationary 70 ring from the entering sides of said movable blades.

6. In a turbine comprising a moving blade carrying element constituting a steam passage, means carried by the blades and by 75 the blade support for rendering said passage of larger area at the entering than at the leaving edges of said blades.

7. In a turbine comprising a moving blade carrying element constituting a steam passage, 80 means between the blades in part at the base and in part at the ends of said blades for rendering said passage of larger area at the entering than at the leaving edges of said blades. 85

8. In a turbine comprising movable and stationary elements each carrying blades, a steam passage formed between two successive blades of each element having inwardly beveled deflecting surfaces at its ends on the 90 fluid entering blade edges, the leaving side being narrower as compared with the entering side.

9. In a turbine, a blade supporting element having a circumferential beveled shoulder for contracting the steam passage between the blades at the blade base, and a shroud ring connecting the ends of a plurality of blades having a beveled surface for contracting the steam passage at its opposite end between the blades. 100

In testimony whereof I affix my signature, in presence of two witnesses.

JOHN F. METTEN.
